CLAIM

The ornamental design for a door hook assembly, as shown and described.

DESCRIPTION

FIG. 1 is a front left perspective view of a door hook assembly.

FIG. 2 is a front elevational view of the door hook assembly of FIG. 1.

FIG. 3 is a left side view of the door hook assembly of FIG. 1.

FIG. 4 is a rear elevational view of the door hook assembly of FIG. 1.

FIG. 5 is a top plan view of the door hook assembly of FIG. 1; and,

FIG. 6 is a bottom plan view of the door hook assembly of FIG. 1.

The dash lines in FIGS. 1-6 are for illustrative purposes only showing environmental subject matter and form no part of the claimed designs.
